UNITED STATES PATENT OFFICE.

REGINALD VANDEZEE FARNHAM, OF SKELMORLIE, AYRSHIRE, SCOTLAND.

DISINFECTOR ATTACHMENT FOR THE FLUSHING ARRANGEMENTS OF WATER CLOSETS
AND THE LIKE.

Application filed November 20, 1922. Serial No. 601,980.

To all whom it may concern:

Be it known that I, REGINALD VANDEZEE FARNHAM, a subject of the King of the United Kingdom of Great Britain and Ireland, and residing at Skelmorlie, Ayrshire, Scotland, have invented a certain new and useful Improvement in Disinfecter Attachment for the Flushing Arrangements of Water Closets and the like, of which the following is a specification.

This invention relates to disinfecter attachments for the flushing arrangements of water closets and the like of the type which are operated by the main flushing stream and which are arranged to deliver disinfectant after the flushing operation.

Disinfecter attachments of said type usually include a lever projecting into the main flushing stream and into a mixing chamber, the lever being adapted to operate a valve controlling the delivery of disinfectant from a container to the mixing chamber and serving to divert part of the main flushing stream into said chamber.

The employment of a lever common to the flushing pipe and the mixing chamber renders it necessary to arrange the disinfecter attachment contiguous to the flushing pipe.

The present invention dispenses with the lever, so that, in the event of there being no accommodation for the attachment next to the flushing pipe, the attachment may be conveniently located remote from the pipe.

In the accompanying drawing, Fig. 1 is a vertical section and Fig. 2 a plan.

The disinfecter attachment shown includes a container 1 for disinfectant and a mixing chamber 2 adapted for convenient attachment to a wall for example by screws penetrating lugs 3. For permitting a quantity of disinfectant to pass from said container to said chamber there is fitted to the container a valve device comprising a cone 4 having an outlet 5 and a cone 6 nesting with the cone 4 and movable relatively thereto, so as, when raised, to discharge the disinfectant trapped in the space between the cones. A scoop 7 connected by a conduit 8 to the chamber 2 projecting into the main flushing pipe 9 serves to divert part of the main flushing stream into the chamber 2. In the conduit line between the scoop 7 and the interior of the chamber 2 there is dis-

posed an inlet- and discharge-controlling member comprising a pipe 10 having an unrestricted delivery opening 11 at a high level and a restricted drain outlet 12 at a low level, the opening 11 permitting rapid inrush of water into said chamber during the flushing operation and the outlet 12 permitting restricted discharge from said chamber through the conduit 8 and through the scoop 7 of admixed disinfectant and water after the flushing operation. A float 13 connected by a rod 14 to the cone 6 is adapted to actuate said valve device once for every inrush of water into the chamber 2.

The contents of the scoop are drained by a perforation 15.

I claim:

1. Disinfecter attachment for the flushing arrangements of water closets and the like comprising a container for disinfectant, a mixing chamber, a valve device for permitting a quantity of disinfectant to pass from said container to said chamber, a scoop connected to said chamber and projecting into the path of the main flushing stream so as to divert part of said stream into said chamber, an inlet- and discharge-controlling member interposed between said scoop and said chamber for permitting inrush of water into said chamber during the flushing operation and restricted discharge from said chamber through said scoop of admixed disinfectant and water after the flushing operation, and a float adapted to actuate said valve device once for every inrush of water into said chamber.

2. Disinfecter attachment for the flushing arrangements of water closets and the like comprising, a container for disinfectant, a mixing chamber, a valve device for permitting a quantity of disinfectant to pass from said container to said chamber, a scoop connected to said chamber and projecting into the path of the main flushing stream so as to divert part of said stream into said chamber, a pipe communicating with the scoop and having an unrestricted delivery opening located at a high level, and a restricted drain outlet at a low level in said chamber, for permitting unrestricted inrush of water into said chamber during the flushing operation and restricted discharge from said chamber through said scoop of admixed disinfectant and water after the flushing oper-

ation, and a float adapted to actuate said valve device once for every inrush of water into said chamber.

3. Disinfecter attachment for the flushing pipes of water closets and the like comprising a container for disinfectant, a mixing chamber, a valve device for permitting a quantity of disinfectant to pass from said container to said chamber, a scoop projecting 5 into the main flushing pipe, a conduit connecting said scoop with said mixing chamber so as to conduct the part of the main flushing stream intercepted by the scoop into said chamber, an inlet- and discharge-controlling 10 member interposed between said scoop and 15

said chamber for permitting inrush of water into said chamber during the flushing operation and restricted discharge from said chamber through said scoop of admixed disinfectant and water after the flushing operation, and a float adapted to actuate said valve device once for every inrush of water into 20 said chamber.

In testimony whereof I have signed my name to this specification in the presence of 25 two subscribing witnesses.

REGINALD VANDZEE FARNHAM.
